UNITED STATES PATENT OFFICE.

RALPH WALDO CROSS, OF DALLAS, TEXAS.

WEATHER-STRIP.

1,247,377.

Specification of Letters Patent.

Patented Nov. 20, 1917.

Application filed January 27, 1917. Serial No. 144,885.

To all whom it may concern:

Be it known that I, RALPH W. CROSS, a citizen of the United States, and a resident of Dallas, in the county of Dallas and State 5 of Texas, have invented a new and Improved Weather-Strip, of which the following is a full, clear, and exact description.

My invention relates to the type of weather strips comprising mating members applied respectively, to the door or window frame, and to the door or window, the one member presenting a groove and the other member a tongue to enter the groove.

In certain weather strips of the type referred to a channel bar and other expedients are employed, designed to trap the water, or otherwise prevent the water entering beneath the sash or door, but wind or draft forces the water between the tongue and groove members comprising the weather strip, causing annoyance and not infrequently damage.

The prime object of my invention is to provide a weather strip of the type referred to, which is rain proof, draft proof, durable, compact, and easily applied, and one that will not result in the sash or door sticking or binding but which will be self-adjusting under conditions due to shrinking or swelling of wood structures, or following the settling of the house or like contingencies.

The distinguishing features of my invention and the advantages will appear as the description proceeds.

Reference is to be had to the accompanying drawings forming a part of this specification in which similar reference characters indicate corresponding parts in all the views.

Figure 1 is a transverse vertical section of a weather-strip showing my invention embodied in the groove member of a casement window at the bottom to co-act with a known form of channel bar presenting a tongue, the view showing the window partly open;

Fig. 2 is a view similar to Fig. 1 but showing the window closed;

Fig. 3 is a horizontal section on the line 3-3, Fig. 1, showing the application of the invention to the window and frame at a side thereof;

Fig. 4 is a fragmentary view in horizontal section in the same plane as Fig. 3, showing on a larger scale, the parts indicated at the upper portion of Fig. 3;

Fig. 5 is a transverse vertical section showing the upper and lower sashes of a sliding window, equipped with a form of my invention at the meeting rails of the sashes, at the bottom and sides of the lower sash, and at the top and sides of the upper sash;

Fig. 6 is a fragmentary view in vertical section on an enlarged scale of the devices shown at the upper right hand corner of Fig. 5.

Referring more particularly to Figs. 1 to 4 which show the invention applied to a casement window at the bottom and at a side thereof, the letter A indicates the sill; B, the window frame; C, the sash; c a groove in the bottom rail of the sash; and c' a vertical groove in the side stile of the sash.

The numeral 10 indicates a known form of channel bar which is suitably secured to the sill A as by screws 11, said bar presenting a vertical splash member 12 at the outside, a lower inner wall 13 terminating at its upper end in an approximately horizontal tongue 14, the splash member 12 having drain holes 15 therein.

Ordinarily, in practice the rigid tongue 14 is received in a groove in the sash presenting rigid walls so that even a slight shrinkage of the sash or frame or a slight settling of the building will throw these rigid members out of line, thereby not infrequently preventing the sash closing tight, thus making the conditions worse than would be the case if no rigid tongue and mating groove were employed. Moreover, in winds and storms, water trapped in the channel bar 10 is forced over the inner wall 13 of the channel bar by wind entering the holes 15. To overcome the objections referred to, I provide self-adjusting elements so arranged as to insure an effective contact between the channel bar 10 or equivalent devices presenting a tongue, and the surfaces engaged by these in the mating groove. Thus, in the bottom rail of the sash C I provide at the groove c an element 16 identified generally as the groove member, the bar 10 and its element 14 being generally referred to as the tongue member of the strip. The element 16 is formed of resilient sheet metal and presents a vertical drip member 17 at the front. At the upper end of the drip member 17 the material of the element 16 is returned on itself at the inside and extends from the top of the groove c obliquely

downward in the form of a resilient member 18 disposed as an inclined plane in the groove *c* across the path of movement of tongue 14. At the lower end the resilient member 18 is return bent in curved form thus constituting an auxiliary channel or groove 20 within the groove *c* to receive the end of the tongue 14.

In the auxiliary channel 20 at the open front end thereof is housed a tiltable and yielding contact element 19, angular in cross section, the members being of unequal width, the upper member of the element 19 being the wider and inclining rearwardly while the shorter member of said element rests on the bottom of the auxiliary channel 20. The element 19 is retained by an upturned lip 22 on the bottom wall of the channel 20 at the front of the latter. A resilient controlling element 21 is also housed in the auxiliary channel 20 and is itself approximately U-shape or V-shape in cross section presenting diverging upper and lower walls, the said walls being forwardly disposed and integral with each other at the back or toward the inner wall of the groove *c*.

The arrangement is such that as the tongue 14 enters the groove *c* it will engage the oblique resilient member 18 and raise the same, thus raising the returned channel end 20 thereof and carrying the tiltable member 19 and the resilient controlling member 21 upwardly. In the continued inward movement of the tongue 14, it will engage the rearwardly inclined upper member of the element 19, thus tilting the latter as indicated in Fig. 2, until the said tongue 14 passes over the element 19 and engages the upper wall of the controlling member 21. Thus, an effective contact results between the tongue 14 above and below the same, and the line of contact between the said tongue 14 and the different surfaces presented by the members 18, 19 and 21 will vary with the shrinkage or expansion of the sash or frame, or with the settling of the building, so that wind and rain will be excluded under all conditions and the mating tongue and groove members will accommodate themselves to any variation in their relative positions.

The structural embodiment of the invention is varied according to the position of the tongue and groove elements, whether these be respectively on the sash or frame. Thus, at the side of the door or window and the jamb, the coacting tongue and groove members are arranged. In the form shown in Figs. 1 to 4, a vertically arranged member 10^a is applied to the jamb *b* of the frame *B* to constitute generally a tongue member, being formed with a tongue 14^a as best seen in Fig. 4, while at the adjacent edge of the window *C*, a member designated generally as 16^a is secured, and may consist, as shown,

of a plate applied to the vertical edge of the sash at the outer side of a rabbet *c'* therein. The said member 10^a is resilient and at its free edge is return bent to produce the tongue 14^a which forms with the body of the member 10^a, a channel 20^a to receive the member 16^a. In the channel is an angular element corresponding with the element 19 and held yieldingly and rockable in the channel 20^a, there being a lip 22^a on the terminal of the tongue 14^a. A resilient controlling element 21^a corresponding in general with the controlling element 21, exerts its pressure on the element 19^a. Upon the closing of the window *C*, the tongue 14^a will be received in the rabbet *c'* beneath the element 16^a. The said element will pass over the upper edge of the element 19^a between the same and the controlling member 21^a to give effective weather-excluding contact between the co-acting tongue and groove members. The resiliency of the member 10^a will permit the tongue 14^a thereon to accommodate itself to any variation in the position of the element 16^a.

In the form shown in Fig. 5, the invention is embodied in a sliding window involving upper and lower sashes, the co-acting elements being applied to the meeting rails of the sashes, and to the frame and sashes at the bottom and sides of the lower sash, and at the top and sides of the upper sash. Thus, the tongue element 10^b having the tongue 14^b is applied to the window frame *B'* at the sides of and beneath the lower sash *C'*. A groove *c'* is produced in the sash *C'* at the sides and bottom and receives a groove member 16^b in which is an angular yielding and rockable element 19^b, corresponding with the elements 19, 19^a, the same being retained by a lip 22^b on the tongue element 16^b and by a resilient controlling element 21^b corresponding with the elements 21, 21^a.

The upper sash *C'* has a groove element 16^c forming a lining for the groove *c'* in the top rail and side stiles of the sash, while the mating tongue member designated generally by the numeral 10^c is suitably secured to the lintel or top rail of the frame *B'* and the sides thereof and presents a tongue 14^c having a lip 22^c, a yielding tiltable element 19^c, and a U-shaped resilient controlling member 21^c which is received at the bend thereof in a depression 10^d in member 10^c, and bears at the ends of its arms on the members of the angular element 19^c. The meeting rails of the sashes similarly have the mating tongue and groove members, there being a groove member 16^c in the form of a channel applied to the inner face of the bottom rail of the upper sash, while a tongue member 14^c is applied to the opposed face of the top rail of the lower sash, said tongue member having the tiltable yielding element 19^c and the resilient con-

trolling element 21^e integral with the base of the tongue member, said tongue member having the lip 22^e corresponding with the lips in the previously described constructions. The tongue 14^e is received in the groove presented by the member 16^e while the outer wall of said groove member 16^e will engage the element 19^e and pass between the same and the opposed surface of 29 the top rail of the sash C^e.

In all the forms the angular rockable element (19, 19^a, etc.,) has a main contact member presenting an inclined plane in the path of the mating member and receding 15 from the front or base formed by the rearwardly disposed flange on said rockable element, and in all the forms also the controlling element (21, 21^a, etc.,) resiliently bears against the said flange yieldingly holding 20 the same against the opposed surface of the member supporting the rockable element.

Having thus described my invention I claim as new, and desire to secure by Letters Patent:—

1. In a weather strip comprising mating elements presenting, respectively, a tongue and a groove, a yielding contact strip rockably supported on one of said elements and presenting a member disposed obliquely in the path of movement of the other of said mating elements, said member receding from its rockably supported base and presenting a free edge over which said other element 35 may pass in contact with the same, and a resilient controlling element on said supporting element and yieldingly resisting rocking movement of said strip.

2. In a weather strip comprising mating 40 elements presenting a tongue and a groove, a contact strip rockably supported on one of said elements in a path to contact with the other of said elements, said strip being angular in cross section presenting a member receding from the front thereof in an inclined plane to engage by its free edge with the said other element, and having a base flange resting on the supporting element; together with a resilient controlling 45 element bearing on the said flange.

3. In a weather strip comprising mating 50 elements having respectively, a tongue and a groove, a resilient strip supported for bodily rocking on one of said elements in addition to its resiliency, and disposed in the path of the other of said elements and presenting a member oblique to the said path, and over which said other element may 55 pass in contact with the free edge thereof.

4. In a weather strip comprising mating 60 elements having respectively, a tongue and a groove, a strip rockably supported on one of said elements in the path of the other of said elements and oblique to said path; together with a resilient controlling element,

said strip having a member against which said controlling element bears.

5. In a weather strip comprising mating elements having respectively, a tongue and a groove, a strip of inherently resilient material, and means on one of said elements on which said strip is bodily rockable in the path of the other of said elements in addition to yielding because of its resiliency, said strip having a member presenting an inclined plane oblique to the said path.

6. In a weather strip, an element presenting a tongue, a mating groove element, and means associated with one of said elements to effect yielding contact with the other element, said means including a channel, a rockable contact element housed in said channel and angular in cross section, adapted to contact with the other of said mating elements, and a resilient controlling element 85 U-shaped in cross section, and also housed in said channel and bearing against said angular element.

7. In a weather strip, an element presenting a tongue, a second mating element presenting a groove, and means in said groove to effect yielding contact with the tongue, said means including a member presenting a channel adapted to receive the tongue, and a strip rockably housed in said channel, oblique to the path of the tongue and yieldable to the passage of the tongue thereover; together with a resilient controlling element also housed in said channel, the said strip having a member on which the said controlling element bears.

8. A weather strip element adapted to receive a tongue to co-act therewith, said element including a plate, a member thereon forming a channel at the inner edge, means to secure the front end of the plate, said plate extending in the form of an inclined plane from the said channel member to the said front end, and a yielding contact strip in said channel.

9. A weather strip element adapted to receive a tongue to co-act therewith, said element including a plate, presenting a channel at the inner end, means to secure the outer end of the plate, said plate extending in the form of an inclined plane from the said channel to the said front end, a vertical drip member depending from the said element at said front end, and a yielding contact strip in said channel.

10. In a weather strip, a groove element and a tongue element, one of said elements being bodily yieldable when engaged by the mating element, said yieldable element presenting a channel, a rockable element in said channel, and a resilient controlling element for said rockable element.

11. In a weather strip of the tongue and groove type, a tongue element adapted to be received in the mating groove element, said

1. tongue element presenting a returned lip at its free end, a contact element rockable on said tongue, behind said lip, and a resilient controlling element on the tongue and bearing against said rockable element.
2. In a weather strip, mating tongue and groove elements, one of said elements having a returned lip, a contact element rockable on the tongue behind said lip and adapted to yieldingly engage the other of said elements, and a resilient controlling element on the tongue and bearing against said rockable element.
3. In a weather strip, mating tongue and groove elements, one of said elements presenting a channel, one wall of said channel having at its free end a returned lip, a rockable contact element in the channel, behind said lip, and a resilient controlling element housed in said channel and bearing on said rockable element.
4. A weather strip comprising tongue and groove elements, one of said elements being in the form of a plate adapted to be fixedly secured at one end and presenting an inclined resilient portion to lie oblique to the path of the mating element, for engagement by the latter, said yielding portion terminating in a channel and a contact element in said channel to engage said mating element.

RALPH WALDO CROSS.
